UNITED STATES PATENT OFFICE.

FRANK E. HOUSH, OF BRATTLEBOROUGH, VERMONT.

DESIGN FOR AN ADVERTISING-CARD.

SPECIFICATION forming part of Design No. 15,469, dated October 21, 1884.

Application filed July 2, 1884. Term of patent 3½ years.

To all whom it may concern:

Be it known that I, FRANK E. HOUSH, of Brattleborough, in the county of Windham and State of Vermont, have invented and produced a new and original Design for an Advertising-Card, of which the following is a specification.

My design consists in a peculiar ornamentation of an advertising-card, the leading features of which are a star in the center of the card, at or near its top, ornamental circular lines or rings at each end of the card, and parallel stripes across the face of the card on either side of said rings.

Reference is to be had to the accompanying drawing, forming part of this specification, which represents a face view of a card having my new design.

The central upper portion of the card is decorated on its face with a star, *b*, and each end of the card with upper and lower circular lines or rings, *c c*. Across the face of the card, on each or both sides of said rings, are parallel stripes *d e*, leaving a space, *f*, between them.

I claim—

1. The design for an advertising-card herein shown and described, the same consisting of the central star, *b*, on the upper portion of the face of the card, and circular lines or 30 rings *c c* on opposite ends of said face.

2. The design for an advertising-card herein shown and described, the same consisting of circular line or ring ornamentations *c c* on opposite ends of the face of the card, and 35 stripes *d e*, and *f* across the face of the card on the sides of said rings.

3. The design for an advertising-card herein shown and described, the same consisting of a central star, *b*, on the upper portion of 40 the face of the card, circular lines or rings *c c* on opposite ends of said face, and the stripes *d e f* across the face of the card.

FRANK E. HOUSH.
